UNITED STATES PATENT OFFICE.

WILLIAM H. EBSARY, OF BUFFALO, NEW YORK.

WEARING-APPAREL.

1,041,711.

Specification of Letters Patent. Patented Oct. 15, 1912.

Application filed March 30, 1909, Serial No. 436,682.

To all whom it may concern:

Be it known that I, WILLIAM H. EBSARY, a citizen of the United States, residing at Buffalo, in the county of Erie and State of New York, have invented a certain new and useful Improvement in Wearing-Apparel, of which the following is a specification.

This invention relates to an improved article of wearing apparel and mainly to a reversible cuff for shirts and other articles of apparel which is formed by folding an integral extension of the sleeve of the article.

15 The object of the invention is to simplify and cheapen the construction of cuffs of this class and at the same time strengthen the same by making the cuff integral with the sleeve.

20 The invention also relates to certain details of construction which will be herein-after described and claimed reference being had to the accompanying drawings in which adaptations of the invention are illustrated.

25 Figure 1 is a face view of the flat cuff blank of one form of the invention together with a fragment of the sleeve with which it is integral. Fig. 2 is a transverse section through the cuff of one form of the invention and a portion of the sleeve with which it is integral, the outlines of the cuff folds being exaggerated to show the construction. Fig. 3 is a fragmentary side view of a sleeve and cuff illustrating the cuff turned in one 35 position. Fig. 4 is a fragmentary side view of a sleeve and cuff illustrating the cuff reversed or turned oppositely from the position shown in Fig. 3.

40 In referring to the drawings in detail like numerals designate like parts.

In this invention the cuff is of a reversible character, so that it can be turned over upon the outer end of the sleeve, and it is formed by folding an extension of the sleeve upon 45 itself to make two or more superimposed plies of material which are secured together by sewing or other suitable means and connect integrally to the sleeve at or near the central longitudinal line of the cuff.

50 In the form of the invention shown in Figs. 1 and 2, the flat rectangular extension 1, of the sleeve 2 is folded upon the transverse dotted lines 3, 4 and 5 and 6 to form a cuff which is integral with the sleeve. In 55 folding or looping the material of the extension it is preferably bent or folded in-

wardly at the margins of the loop on the transverse dotted lines 7 and 8 to form four ply marginal sides, as shown in Fig. 2, to stiffen and strengthen the construction of 60 the sides of the cuff. The lines 7 and 8 are located centrally between the lines 3 and 4 and 5 and 6, as shown in Fig. 1. By this means a cuff is produced having each of its side margins composed of two folded and 65 superimposed portions, each of which comprises two thicknesses of cloth joined at their outer edge by an integral fold or band which forms a smooth surfaced hard wearing rounded end constituting one corner of 70 a side edge of the cuff. The advantage of this construction is that the side margins of the cuff are stiffened and strengthened and a double fold edge is secured without in any way cutting or exposing the raw edge 75 of the material. By this means the side edges of the cuff are composed of two independent rounded edges arranged side by side and each constituting a corner wearing surface. Another advantage is that the 80 groove or recess between the two portions constitutes a pocket for starch to stiffen the cuff at its side margins. The longitudinal central line of the cuff is also stiffened and strengthened by folding the integral portion 85 of material intermediate the cuff and sleeve in a serpentine or zigzag manner on the dotted lines 9 and 10, shown in Fig. 1. In making up this form of the cuff, rows of stitching 11 and 12 are sewed respectively 90 through the side margins and the central portion as shown in Fig. 2.

It will be noticed by referring to Figs. 1, 3 and 4 that the portion of the sleeve which is lapped by the cuff is sufficiently wider 95 than the cuff to provide side flaps 13 and 14. These side flaps 13 and 14 project beyond the ends of the cuff when folded as shown in Figs. 3 and 4, and are respectively provided with a button 15 and button-hole 16. 100 By buttoning these flaps, which is easily performed owing to the soft flexible and unstarched character of the goods in the sleeve, that portion of the cuff below the button-holes for the ordinary cuff buttons is drawn 105 together and is supported in proper position on the arm of the wearer.

The cuff in this form of the invention can be made very quickly by any fairly skilled operator by first bending the inner 110 portion of the extension on the dotted lines 9 and 10 to form the central stiffening por-

tion, then bending the material laterally to one side to form approximately one half of the inner layer of the cuff folding the same laterally inwardly and outwardly in a series 5 of short folds on the three bends 5, 6 and 8 to form a four ply side edge having two rounded corners, then continuing the material laterally to the end of the opposite side to form the outer layer of the cuff, then folding it laterally inwardly and outwardly in a series of short folds on the three bends 3, 4 and 7 to form a four ply side edge having two rounded corners on the side opposite the first mentioned side edge and finally lapping 10 the extreme outer end of the extension inwardly over the inner end or beginning of the first mentioned portion, as shown in Fig. 2 to form the other half of the inner layer of the cuff. The central serpentine folds 15 and the lapping parts are now sewed or fastened by a single row of stitching 12, and the four ply side margins formed by the folds 3, 4 and 7, and 5, 6 and 8 are likewise sewed or fastened by single rows of stitching 11, as clearly shown in Fig. 2.

The principal advantage of this invention resides in the forming of the cuff integral with the sleeve by looping an integral extension of the sleeve.

30 In the ordinary cuff the raw edge of the material forms the side edge of the cuff and is exposed to wear and in turn after considerable use becomes rough and ragged forming an edge which chafes the skin of 35 the wearer. In this improvement the raw edge of the material is not cut or exposed, the side edge of the cuff being formed by folding or bending the material upon itself thereby exposing only the side surface of 40 the material and producing a smooth, round, hard wearing surface.

I claim.

1. In an article of apparel, a sleeve and a

reversible cuff comprising an extension of 45 rectangular outline narrower in width than the sleeve and integral with said sleeve; said extension projecting from the outer end of the sleeve and being bent in a serpentine manner to form a central cuff stiffening portion, then laterally to one side, then folded laterally backward over the first mentioned lateral fold and finally folded laterally beneath the second mentioned fold with its inner margin lapping over the inner margin of the first mentioned fold, and a single row 50 of stitching passed through the serpentine cuff stiffening portion and the lapping inner margins.

2. In an article of apparel, a sleeve and a 55 reversible cuff integral with said sleeve and comprising an extension projecting from the sleeve; said extension being first bent backward and forward or in a serpentine manner in a series of short folds to form a 60 central multi-ply stiffening portion, then 65 extended laterally to one side to form approximately one half of the inner ply of the cuff, then folded laterally in a series of short folds to 70 form a four ply side edge having two rounded corners, then extended laterally to form the outer ply of the cuff, then folded laterally in a series of short folds to 75 form a four ply side edge having two rounded corners on the side opposite the first mentioned side edge, and finally extending 80 the extreme end portion inwardly and lapping it over the inner margin of the first mentioned fold to form the other half of the inner ply of the cuff, and rows of stitching passed through the center and side margins of the cuff.

WILLIAM H. EBSARY.
